UNITED STATES PATENT OFFICE.

JOHN A. MACDOWELL, OF ST. LOUIS, MISSOURI.

BAFFLE WALL TOOL.

Application filed April 9, 1926. Serial No. 100,786.

This invention is a special tool for use in building or repairing the baffle walls of water tube boilers, where such walls are composed of or include outer shells of blocks 5 or tiles which overlap one another from top to bottom, as described in my separate application for patent covering a special form of such tile.

The object of this invention is to provide 10 a tool by the use of which the form of tiled baffle walls referred to may be readily constructed in water tube boilers.

In the drawing—

Fig. 1 is a perspective view, showing the 15 tool in use in constructing a tiled baffle wall;

Figure 2 is a view of the tool, holding the special form of tile for which it is designed;

Figure 3 is a view of the said special 20 form of tile, apart from the tool;

Figure 4 is a front elevation of the tool alone;

Figure 5 is a rear elevation of the tool;

Figure 6 is an edge view of the tool.

25 This invention is a tool for use in connection with the form of baffle tile illustrated at 1, and which is flat, having the parallel oppositely disposed beveled ends 2 tapering from the opposite faces of the tile 30 as shown at 3, and the intermediate arcuate cut-outs 4, which are adapted to laterally engage two adjacent water tubes 5 as mounted in a water boiler (not shown).

This tool comprises a tile holder 6 of sheet 35 metal, the holder being formed of an arcuate or bow-like shape in the plane of the sheet of metal, as shown in Figures 4 and 5. One end of this holder is bent slightly out of the said plane, as shown at 7, so as to conform to either of the beveled ends 2 of the tile 1, when the tile is properly positioned upon the tool. The parallel extremities of the holder are then bent out substantially perpendicularly to the body of the holder, 45 to form flanges 8, to which are secured tile clamps 11 made of strips of relatively thin spring metal, and which are adapted to resiliently engage the straight parallel edges of the ends 2 of the tile when the same is placed in the holder. A working handle 9 is hinged at 10 to the back of the holder 6, the hinge 10 being set askew as shown, with reference to the medial or axial line connecting the flanged ends of the holder, in order 50 to facilitate the operation of the tool in the manner now to be described.

In the use of this tool, a tile 1 is positioned upon the tool, as shown in Figure 2 where it is releasably held by the spring clamps 11. The handle 9 is then turned 60 flat against the back of the holder, and the holder carrying the tile is then inserted obliquely up through one of the "alleys" between the rows of tubes. When the two laterally adjacent tubes, as 5, are reached, 65 transversely between which it is desired to locate the tile, one of the arcuate ends of the tile is positioned against one of the tubes. Then by manipulation of the handle 9 and drawing same out from the back of the 70 holder and at the same time keeping the horns of the arcuate end of the tile first placed in engagement with the tube, astraddle of that tube, the opposite arcuate end of the tile is caused to rise and the tile to 75 assume a transverse horizontal position between the two tubes 5, with the two arcuate ends 4 of the tile in lateral engagement with the two tubes 5. The process is repeated with additional tiles until the wall or shell 80 is completed; the tiles being located in a common plane and in overlapped relation, as explained in my separate application covering the subject matter of the said tile.

85 While I have herein described a certain specific manner and method of constructing and assembling the elements of my invention, it is understood that I may vary from the same in minor details, not departing from the spirit of my invention, so as best 90 to construct a practical device for the purpose intended, as defined in the appended claims.

I claim:

1. A tool of the kind described, comprising a flat tile holder having two opposite ends thereof made parallel; resilient tile clamps fixed at the said two opposite ends of the holder for releasably engaging a tile; and a handle hinged at the back of the 100 holder.

2. A tool of the kind described, comprising a flat tile holder, arcuate in the plane of the holder, two opposite ends thereof being parallel; resilient tile clamps fixed at 105 the said two opposite ends of the holder for releasably engaging a tile; and a handle hinged at the back of the holder.

3. A tool holder of the kind described, comprising a flat tile holder arcuate in its 110 own plane and having an end thereof bent slightly out of its plane, the said holder

having two opposite parallel extremities; means at the said two opposite ends of the holder for releasably engaging a tile; and a handle hinged askew at the back of the holder.

4. In combination with a baffle tile of the kind described, a tool of the kind described, comprising a flat tile holder arcuate in its own plane and having an end thereof bent

slightly out of its plane, the said holder 10 having two opposite parallel extremities; means at the said two opposite ends of the holder for releasably engaging a tile; and a handle hinged askew at the back of the holder.

15

In testimony whereof I affix my signature.

JOHN A. MacDOWELL.
